UNITED STATES PATENT OFFICE.

WILLIAM J. DELANEY, OF PLAINFIELD, CONNECTICUT, ASSIGNOR OF ONE-HALF TO
GEORGE GOSELIN, OF PLAINFIELD, CONNECTICUT.

ATTACHMENT FOR COMBER MACHINES.

Application filed February 5, 1925. Serial No. 7,077.

To all whom it may concern:

Be it known that I, WILLIAM J. DELANEY, a citizen of the United States, residing at Plainfield, in the county of Windham and 5 State of Connecticut, have invented certain new and useful Improvements in an Attachment for Comber Machines, of which the following is a specification.

This invention relates to an attachment 10 for a comber machine, which is principally used in combing wool, flax and the like, the attachment providing a means for removing the lint which collects on the machine, during the usual operation thereof. 15 One of the important objects of the present invention is to provide an attachment of the above mentioned character, which includes a suction operated means for removing the lint which collects between the various 20 pairs of feed rollers and the usual cotton laps and collecting such lint in a suitable receptacle. This attachment thereby keeps the material and the comber machine clean, thus permitting the proper operation of the 25 machine.

A still further object of the invention is to provide an attachment of the above mentioned character, which is of such construction as to enable the same to be readily and 30 easily secured on any conventional type of comber machine, the attachment being further simple in construction, inexpensive, strong and durable, and well adapted for the purpose for which it is designed.

Other objects and advantages of the invention will become apparent during the course of the following detailed description.

In the accompanying drawings, forming a part of this application, and in which like 40 reference characters indicate corresponding parts throughout the several views:

Figure 1 is a side elevation of the lint removing attachment embodying my invention, showing the same in position on a 45 comber machine, and

Figure 2 is a vertical sectional view, through one of the receiving pockets and the suction pipe associated therewith.

In the drawing, wherein for the purpose 50 of illustration is shown the preferred embodiment of my invention, the numeral 1 designates generally a comber machine of any well-known construction, and only such parts thereof need be mentioned, it is 55 thought, as form parts of the present in-

vention. The usual stock rollers of the comber machine are designated generally by the numeral 2 and the feed rollers cooperating therewith at 3. These rollers, which are arranged in pairs, in the manner well-known in 60 the art, are furthermore arranged in spaced relation with respect to each pair, as is also well-known in the art.

In the usual operation of the machine, in 65 combing the wool, flax, or the like, considerable lint is thrown off and the same collects on the machine between the pairs of rollers and oftentimes results in the material leaving the machine with a certain 70 amount of dirt. Furthermore, the collection of the lint on the machine will, in time, affect the proper operation of the machine. In order to overcome the above disadvantages, I have provided an attachment which 75 may be readily and easily installed on any conventional type of comber machine and the construction thereof is hereinafter more fully explained.

The attachment comprises a plurality of 80 receiving pockets 4, each of which is open at its top, as clearly illustrated in Figure 2. The receiving pockets 4 are adapted to be disposed between the several pairs of stock and feed rollers, the open top of each pocket being disposed adjacent the bottom of the 85 adjacent feed rollers, as is illustrated more clearly in Figure 1. A collecting chamber 5 is supported on one end of the comber machine, preferably at the forward end thereof, the collecting chamber 5 tapering gradually 90 toward its forward end and to which is connected a suitable outlet pipe 6.

Each of the receiving pockets 4 is operatively associated with the collecting chamber 5, through the medium of the respective 95 suction pipes 7. As is clearly illustrated in Figure 1, the suction pipes are arranged in superposed relation with respect to each other, and any suitable means may be provided for securing the same in such position on the frame of the machine. The suction pipes gradually increase in length from the forward end of the machine to the rear end thereof and the outer end of each pipe terminates in the upwardly disposed portion 105 8, the latter in turn terminating in the rearwardly extending portion 9, which has communication with the respective pockets 4, through the medium of the bulged out portion 10.

A suction fan or the like (not shown) is adapted to be attached to the pipe 6 and as a result, the lint which flies, or is otherwise separated from the material passing from the stock rollers 2 over the feed rollers 3 during the operation of the comber machine, is dropped between the pairs of rollers, and is forced into the various pockets 4 by the suction and the lint which accumulates in the pockets will be discharged therefrom and delivered to the lint collecting or receiving chamber 5.

It will thus be seen, from the foregoing description that an attachment for a comb-
15 er machine has been provided which will prevent any lint from collecting thereon between the rollers, thus enabling the machine to properly operate and keep the material in a clean condition while on the machine.

20 While I have shown the preferred embodiment of my invention, it is to be understood that various changes in the size, shape and arrangement of parts may be resorted to, without departing from the spirit of the invention or the scope of the appended claims.

Having thus described my invention, what I claim is:

1. An attachment for comber machines

wherein the latter includes a plurality of spaced pairs of stock and feed rollers comprising a series of lint receiving pockets, the same being disposed between the adjacent pairs of said rollers, a suction chamber supported on one end of the machine, and a plurality of suction pipes connecting said 30 lint receiving pockets with said suction chamber, said pipes being arranged in superposed relation, and an outlet pipe extending from said suction chamber.

2. In an attachment for a comber machine 40 wherein the same includes a plurality of spaced pairs of stock and feed rollers, a series of lint receiving pockets, each of which is open at its top, said pockets being disposed between said pairs of rollers, the 45 upper portion of each pocket being disposed adjacent the respective feed rollers, a suction chamber supported on the forward end of the machine, a series of suction pipes connecting said lint receiving pockets with said 50 suction chamber, said suction pipes being disposed in superposed relation, and a discharge pipe extending from the forward end of said suction chamber.

In testimony whereof I affix my signature,
WILLIAM J. DELANEY.
